UNITED STATES PATENT OFFICE

JAMES W. EASTON, OF NEW YORK, N. Y., ASSIGNOR TO P. MINTURN SMITH, OF PLAINFIELD, NEW JERSEY, AND WILLIAM D. PERRY, OF BROOKLYN, NEW YORK.

SUPPORT FOR ELECTRIC LAMPS.

SPECIFICATION forming part of Letters Patent No. 449,902, dated April 7, 1891.

Application filed June 19, 1890. Serial No. 355,920. (No model.)

To all whom it may concern:

Be it known that I, JAMES WATSON EASTON, a subject of the Queen of Great Britain, and a resident of the city, county, and State of New York, have invented certain new and useful Improvements in Supports for Electric-Arc Lamps; and I hereby declare that the following is a full, clear, and exact description thereof, reference being had to the accompanying drawings, forming part of this specification.

The object of my invention is the provision of means for supporting an electric-arc lamp which will permit the lamp to be readily suspended at any desired height and will afford a firm support for it and yet allow the lamp to swing freely in all directions without becoming detached from the support.

To this end my invention consists in the novel details of construction and arrangement and combination of parts hereinafter described, and specifically set forth in the claim.

In the accompanying drawings, Figure 1 is a view, partly in section, of my invention as used for supporting a lamp for indoor illumination. Fig. 2 is a plan view thereof as seen from beneath, and Fig. 3 is a detail view of the swinging links or loops by which the lamp is held in place.

Similar letters of reference are used in all the views to designate corresponding parts.

To the ceiling of the room or to any other desirable point is attached the plate A, which forms a suitable support for the binding-posts B, to which the terminals of the line-wires are secured, and for the switch C and its connections, by which the circuit is maintained when the lamp is not in use. To the plate A are also secured two eyes or rings D D, within which are suspended the swinging loops E E, which are preferably constructed of wire bent into substantially the shape shown in the drawings; but I do not wish to limit myself to any specific material therefor. To the rod or extension F, which forms the upper portion of the lamp-frame, are secured two projecting lugs or ears G G, each of which is adapted to rest in the bottom of one of the loops E, as shown in Fig. 1.

I prefer the form of construction herein shown embodying the separable collar H, the sections of which are adapted to be clamped to the extension F by set-screws h, because such construction affords a simple and convenient means of adjusting the height of the lamp. 55

The operation of the device will now be readily understood. When the lamp is not in position the loops E E hang loosely in the eyes D D, as shown by full lines in Fig. 3. The upper end of extension F is made of such shape as to be readily insertible between the loops, and as the lamp is raised the loops are separated and forced out toward the position 65 shown by the dotted lines in Fig. 3, and when the lugs come into contact with them the loops spread out over the top of the lugs and fall into place under them. When it is desired to take the lamp down, it is lifted slightly 70 and turned so that the lugs G are brought between the loops E, and thus released from engagement with them. When the lamp is in position and ready for use, the binding-posts B are connected to the binding-posts f 75 on the lamp by suitable conductors, which are disconnected when it is desired to take down the lamp.

I have shown the lamp suspended from the ceiling of a room; through which the extension F projects into the space between the rafters; but the openings through the plate A and the ceiling are not necessary when the lugs are fixed on the upper extremity of such extension. 85

It will thus be perceived that while my improved device is of the most simple construction it affords a perfectly secure support for the lamp, since, owing to the form of the loops E, which prevents any lateral or twisting 90 movement of the lugs G, the lamp will not be disengaged by any such movement accidentally imparted to it; but the lamp must be lifted bodily to release the lugs from engagement with the loops. At the same time 95 as the lamp is supported so as to swing freely in all directions it will accommodate itself to any sudden shock or movement that may be imparted to it without becoming disengaged from the loops. Furthermore, the lamp 100

may be put in place or removed instantly without any manual manipulation of the suspending devices.

I do not wish to confine myself to a device for supporting electric lamps only, because it may be used to support any object to which the lugs G can be attached.

Having thus described my invention, what I claim as new, and desire to secure by Letters Patent, is—

In a supporting device, the combination of two independent swinging loops E E of sub-

stantially the shape shown, a support therefor, and the extension F, provided with the lugs G, adapted to rest in the bends of the loops and project over the sides thereof, whereby the lugs are prevented from receiving any lateral or twisting movement while supported in the loops, substantially as and for the purposes set forth.

JAMES W. EASTON.
